ROBERT VANDEVORT, OF PITTSBURG, PENNSYLVANIA.

Letters Patent No. 69,051, dated September 17, 1867.

IMPROVED BOOT-HEEL.

The Schedule referred to in these Letters Patent and making part of the same.

TO ALL WHOM IT MAY CONCERN:

Be it known that I, ROBERT VANDEVORT, of Pittsburg, in the county of Allegheny, and State of Pennsylvania, have invented certain new and useful improvements in Metallic Heels for Boots and Shoes; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in a novel manner of constructing and securing metallic heels to boots and shoes.

Figure 1 is a plan view of a metallic plate used for securing the heel in place.

Figure 2, a vertical longitudinal section of the plate and heel in position.

Figure 3 is a top plan view of the heel detached.

Many plans have heretofore been devised for constructing and attaching metallic heels to boots and shoes, but without success. In order to accomplish the desired object of providing a heel that shall be neat in appearance, and that can be securely attached, I first attach to the sole of the boot or shoe a metallic plate, A, of the exact size and outline of the heel, as shown in fig. 1. A portion of this plate projects at the front, as represented by a. This plate A I secure firmly in place by means of rivets or screws. I then construct a hollow metallic heel, as represented by C. This heel is formed with a ledge or shoulder, i, around its inner upper edge, as shown in figs. 1 and 2, which rests against the under surface of the plate A, the upper edge of the heel fitting snugly around the outer edge of the plate A, as shown in fig. 2. In the interior of the heel C is a projection or lug, o, to receive and hold the end of a screw, b, inserted from the upper side of the sole, as shown in fig. 2. At the front side of the heel a thin plate, n, projects, and fits snugly on the projecting part a of plate A, and having a screw, c, inserted through it, as shown in fig. 2.

As is well known, heels are very liable to become detached by kicking or striking them on the front side against objects accidentally. By means of this front projecting plate n this is remedied, as this plate holds them firmly in place. By its fitting snugly all around over the edge of plate A, the heel is prevented from being shoved or displaced sidewise, and is, therefore, securely held in place.

By this means I am enabled to produce a metallic heel that is very light and strong, that can be securely attached, and that may be made as neat and ornamental as a leather heel. When worn on one side they can be very quickly changed from right to left, and *vice versa*, and thus compensate for any uneven wear on the heels.

Having thus described my invention, what I claim, is—

The metallic heel C, with the front projecting lip n, and internal recess or shoulder i, held in place by means of the plate A, secured firmly to the sole, and screws b and c, as herein set forth.

ROBERT VANDEVORT. [L. S.]
